(57) **CLAIM**

The new and ornamental design for a wood pellet, as shown and described.

DESCRIPTION

FIG. 1 is a perspective view of a wood pellet showing our new design,

FIG. 2 is an end elevation thereof,

FIG. 3 is a side elevation thereof, the opposite side elevation corresponding to FIG. 1,

FIG. 4 is a top plan view thereof; and,

FIG. 5 is a bottom plan view thereof.

The wood pellet is of indeterminate length

The broken lines which define the bounds of the claimed design form no part thereof. The claimed design is shown broken away in all views to indicate indeterminate length.
